UNITED STATES PATENT OFFICE.

LORISTON F. AMSDEN, OF BALTIMORE, MARYLAND, ASSIGNOR OF ONE-HALF TO HAROLD C. MITCHELL, OF NEW YORK, N. Y.

DESIGN FOR A SUPPLEMENTARY WAIST FOR MEN'S OVERCOATS.

58,301.

Specification for Design.

Patented July 12, 1921.

Application filed January 15, 1920. Serial No. 351,623. Term of patent 14 years.

To all whom it may concern:

Be it known that I, LORISTON F. AMSDEN, a citizen of the United States, residing at Baltimore, State of Maryland, have invented a new, original, and ornamental Design for a Supplementary Waist for Men's Overcoats, of which the following is a specification, reference being had to the accompanying drawing, forming part thereof.

The figure is a perspective view of the supplementary waist alone.

I claim:

The ornamental design for a supplementary waist for men's overcoats, as shown.

LORISTON F. AMSDEN.
